UNITED STATES PATENT OFFICE.

FRANK JONES, OF CHICAGO, ILLINOIS.

BOTTLE-PACKAGE.

SPECIFICATION forming part of Letters Patent No. 739,604, dated September 22, 1903.

Application filed December 18, 1902. Serial No. 135,716. (No model.)

To all whom it may concern:

Be it known that I, FRANK JONES, a citizen of the United States, residing at Chicago, in the county of Cook and State of Illinois, have 5 invented certain new and useful Improvements in Bottle-Packages, of which the following is a specification, reference being had to the accompanying drawings.

My invention relates to improvements 10 whereby an ordinary bottle may without change in the bottle itself be provided with means adapted to carry a plurality of small packages of material either in liquid or other form, which are intended to be emptied from 15 time to time into the said bottle. The means employed in the construction shown comprises a removable holder adapted to be passed over the neck of the bottle and seated upon the bottle below the neck, such holder being 20 provided with a series of holes into which vials are adapted to be placed.

My invention also includes a casing of such form and proportions as to properly receive the bottle and the vial-carrying holder, to 25 which casing said holder is attached, so that upon lifting the casing from the bottle the vials will also be removed to permit the ready pouring of liquid from the bottle.

My invention also comprises certain details 30 of construction hereinafter particularly pointed out.

The invention is particularly designed for use in connection with ink-bottles, as by it there can be furnished in small compass the 35 material for making a large number of bottles of ink, inasmuch as each vial is intended to be filled with a suitable material which when combined with water in the large bottle will form a quantity of satisfactory ink in 40 such bottle.

That which I believe to be new will be pointed out in the claims.

In the accompanying drawings, Figure 1 is 45 a side elevation of a bottle with the removable holder in place thereon, such holder being partly broken away and a portion of the inclosing casing being in section. Fig. 2 is a vertical section. Fig. 3 is a horizontal section at line 3-3 of Fig. 2. Fig. 4 is a detail, 50 being a perspective view of the removable holder. Fig. 5 is a vertical section through the removable holder and that portion of the casing to which the holder is attached. Fig.

6 is a side elevation of the bottle and the lower portion of the casing as such parts appear when the parts shown in Fig. 5 are removed from the bottle; and Fig. 7 is a view, partly in section, showing the parts represented in Figs. 5 and 6 united and with the cover of the casing raised. 60

Referring to the several figures of the drawings, in which corresponding parts are indicated by the same reference-numerals, 8 indicates the body of a bottle, which bottle may be of ordinary shape and material, the 65 bottle shown having a cylindrical body, above which is a substantially conical-shaped portion 9, carrying the neck portion 10.

11 indicates a holder, preferably made of wood, but which of course may be of any 70 suitable material. In its underface is formed a large recess 12 of a size and shape to adapt the holder to be seated upon the conical-shaped portion 9 of the bottle, a central opening 13 in the holder, through which the neck 75 of the bottle can pass, permitting the holder to be so placed on the bottle. The upper face of the holder is provided with a series of sockets 14, adapted to receive a series of vials 15 or other forms of packages containing material intended to be combined with fluid in 80 the bottle.

The casing for the bottle in the form of construction shown consists of a base 16, that encloses the lower end of the bottle and fits 85 snugly thereon, a long cylindrical body portion 17, and a cover 18 for said body portion.

The base portion 16 does not need to be removed from the bottle during the operations of filling or pouring from the bottle, and it 90 will therefore be always in place to receive upon it the cylinder 17, which must be slipped off whenever any of the contents of the bottle are to be poured out. The holder 11 is attached in any suitable manner to the cylindrical body portion 17 of the casing, as indicated in Fig. 5, so that the removal of such body portion 17 carries with it the said holder and the series of vials 15. This is very desirable, as it effects a saving of time, and the 95 vials are of course much less liable to breakage when removed from and while being removed from the bottle. As clearly shown in the drawings, the sockets 14 are arranged a short distance from the edge of the holder, 100 the distance from the edge being substantially 105

equal to the thickness of the flange of the cover 18, with the result that such flange fits in snugly between the vials and the wall of the body portion 17 of the casing and acts to hold the vials firmly in place.

With my invention employed in connection with inks, for example, the equivalent of a large number of bottles of ink can be stored in a space practically no greater than 10 that occupied by a single bottle, for each vial will be filled with a proper material, which, combined with water, will produce a supply of ink sufficient to fill the bottle. When ink is to be poured from the bottle, the cylindrical body portion 17 is to be lifted off, carrying with it, as before explained, the holder 11 and the series of vials, and is afterward to be replaced over the bottle and the base portion 16 of the casing. By this construction 20 the bottle itself may always be covered and protected by a neat package, the vials will not be apt to be lost or destroyed, and the equivalent of a large number of bottles of ink may be kept in a small space.

25 While my invention is particularly designed for use in connection with inks and ink-bottles, it may of course be used in connection with other liquids and their bottles. I also desire it to be understood that while I 30 have shown and referred to the packages carried by the holder as "vials" I do not limit myself to such form of package.

That which I claim as my invention, and desire to secure by Letters Patent, is—

35 1. The combination with a bottle, of a package-holder provided with a recessed bottom to adapt it to fit upon the upper part of the bottle with said package-holder below the upper end of said bottle, substantially as specified.

40 2. The combination with a bottle, and a casing therefor, of a package-holder within and connected to said casing and adapted to fit around and rest upon said bottle, substantially as specified.

45 3. The combination with a bottle, and a casing therefor, of a package-holder secured to the interior of said casing and adapted to fit around and rest upon said bottle, substantially as specified.

50 4. The combination with a bottle, of a removable casing therefor, and means carried by said casing for supporting a series of packages around the neck of the bottle, substantially as specified.

55 5. The combination with a bottle, and a casing therefor, of a package-holder adapted to be seated upon the upper part of the bottle and provided upon its upper face with means 60 for holding a series of packages, and a cover for said casing having a flange projecting into the space between said packages and said casing, substantially as specified.

65 6. The combination with a bottle, of a package-holder provided with a central opening and with a recessed bottom to adapt it to fit over and upon the upper part of the bottle

with said package-holder below the upper end of said bottle, substantially as specified.

7. The combination with a bottle, of an annular holder having a central opening and a recessed bottom to adapt it to fit over and upon the neck of the bottle and provided in its upper face with a plurality of sockets, substantially as specified. 75

8. The combination with a bottle, of a casing therefor, and an annular holder having a central opening to adapt it to fit over the neck of the bottle and provided in its upper face with a plurality of sockets, said holder being 80 secured to said casing, substantially as specified. 75

9. The combination with a bottle, of a casing therefor, a package-holder upon the bottle, and a cover for the casing having a flange 85 in said casing to surround the packages sustained by the package-holder, substantially as specified.

10. The combination of a bottle, the upper part of the body of which is conical, and a package-holder having in its under face a recess shaped to agree with and to fit against such conical portion with said package-holder below the upper end of said bottle. 90

11. The combination of a bottle and a casing therefor including a body portion, and a base portion removably fitted one within the other, and a cover for the body portion, the bottle being sustained by the base portion, and a package-holder connected with said 100 body portion below said cover.

12. The combination of a bottle and a casing therefor including a body portion, and a base portion removably fitted one within the other and a cover for the body portion, the 105 bottle being sustained by the base portion, and a package-holder surrounding the bottle and connected with said body portion below said cover.

13. The combination of a bottle and a casing therefor, a package-holder inclosed by and connected with the casing and adapted to rest upon the bottle, and means in the casing for steadyng the packages carried by said package-holder. 110

14. The combination of a bottle, a case therefor including a body portion, and a base portion removably fitted within the body portion and snugly receiving the lower portion of the bottle, and a cover for the body portion, a package-holder surrounding the bottle and connected with the body portion, and means upon the cover for steadyng the packages carried by said package-holder. 120

15. The combination of a bottle, a casing 125 member removably surrounding the bottle, and a package-holder secured to the casing member within the same and adapted to rest upon the bottle.

FRANK JONES.
